United States Patent Office

Des. 217,250
Patented Apr. 21, 1970

217,250

DENTAL UNIT

John M. Gardella, Matawan, N.J., and Anthony Ciavattoni, Staten Island, N.Y., assignors to Pennwalt Corporation, Philadelphia, Pa., a corporation of Pennsylvania

Filed Aug. 8, 1969, Ser. No. 18,603

Term of patent 14 years

Int. Cl. D24—03

U.S. Cl. D24—1

*Fig. 5**Fig. 4**Fig. 6*

FIG. 1 is a perspective view of the front, top and one side of the unit;

FIG. 2 is a front elevational view of the unit;

FIG. 3 is a top plan view thereof;

FIG. 4 is a side elevational view, taken from the side opposite that shown in FIG. 1;

FIG. 5 is a rear elevational view thereof; and

FIG. 6 is a vertical sectional view, taken along line 6-6 of FIG. 1.

The broken lines are shown for illustrative purposes and do not form part of the claim.

We claim:

The ornamental design for a dental unit, as shown and described,
